GOLF TEE

Jack W. Pearson, 141 Miami Ave., Elyria, Ohio, and
Thomas H. Davis, 739 Cliffside Circle, Akron, Ohio

Filed May 22, 1963, Ser. No. 75,004

Term of patent 14 years

(Cl. D34—5)

FIG.1

We claim:

The ornamental design for a golf tee, substantially as shown.
